UNITED STATES PATENT OFFICE.

KENNETH A. CRISMON, OF SALT LAKE CITY, UTAH.

PASTE-TUBE HOLDER.

1,270,267.

Specification of Letters Patent. Patented June 25, 1918.

Application filed June 26, 1917. Serial No. 177,061.

To all whom it may concern:

Be it known that I, KENNETH A. CRISMON, a citizen of the United States, residing at Salt Lake City, in the county of Salt Lake 5 and State of Utah, have invented certain new and useful Improvements in Paste-Tube Holders, of which the following is a specification.

This invention relates to paste tube holders and more particularly to means for holding tubes for containing tooth paste, soap in paste form and similar materials.

One of the main objects of the invention is to provide a device of the character stated of 15 simple construction and operation for supporting a compressible tube for containing paste, this supporting device being provided with means for compressing the tube so as to expel the contents thereof. A further object 20 is to provide a casing having means for compressing a tube and for simultaneously forming the tube into a compact bundle or mass so as to occupy but very little space. A still further object is to provide a casing in con- 25 junction with a key for winding a tube and a resilient member for engaging the tube so as to compress the same and expel the contents thereof as the tube is wound upon the key. Further objects will appear from the 30 detailed description.

In the drawings:

Figure 1 is a plan of the blank for forming the casing,

Fig. 2 is an underneath perspective view 35 of the casing,

Fig. 3 is a detail of the key,

Fig. 4 is a central vertical sectional view 40 through the casing,

Fig. 5 is a similar view showing a tube in 45 operative position,

Fig. 6 is a section taken on line 6—6 of Fig. 5,

Fig. 7 is a top plan view of a blank for a 50 modified form of casing,

Fig. 8 is a central vertical sectional view 55 through a modified form of casing,

Fig. 9 is a section taken substantially on line 9—9 of Fig. 8,

Fig. 10 is a plan view of blank for another 60 modified form of casing, and

Fig. 11 is a vertical sectional view through 65 this other modified form.

The blank shown in Fig. 1 of the drawings 70 is provided with the approximately triangular lateral pieces 1 and 2 and the approximately square back 3 and the rectangular

front 4. The pieces 1 and 2 are provided with the hook slots 5 and 6, respectively, extending inward from the outer edge thereof. This blank is bent along the dotted lines indicated 60 in Fig. 1 of the drawings, so as to produce the casing shown in Fig. 2, having the tapering side walls 1 and 2, squared back 3, and rectangular front 4, the walls 1 and 2 being provided with the vertically extending hook 65 slots 5 and 6, respectively. This casing is secured to any suitable fixed object by means of a screw 7 or other securing element inserted through the same. A broad leaf spring 8 is secured to the top of the casing 70 adjacent the back 4 thereof, at its inner end, by means of rivets 9. A tapering wedge block 10 is interposed between spring 8 and the top 11 of the casing, the spring being bent at an angle so as to be directed downwardly and outwardly as in Fig. 4 of the drawings. Spring 8 is of such length as to extend beyond the slots 5 and 6. A key 12 such as that shown in Fig. 3 of the drawings is rotatably mounted in the hook portions of 80 slots 5 and 6. This key is provided with a central longitudinally extending slot 13 which is adapted to receive the flattened end portion 14 of a compressible tube 15 of tin foil or other suitable material which contains the paste to be expelled. When the key 12 is in operative position, the spring 8 is held pressed downward into tight engagement therewith, as in Fig. 5 of the drawings. By rotating the key 12 the tube 15 will be 90 wound onto the same, the pressure of spring 8 on the tube serving to force the contents of the tube out of the threaded nipple 16 at the lower end thereof as the tube is wound onto the key. By this means, any desired amount 95 of material may be forced out of the tube, the tube being flattened and wound upon the key 12 during this operation. When the tube has been emptied, the key may be readily removed from the casing by being lifted 100 out of the hook portions of the slots 5 and 6 after which the empty tube may be removed and a new tube inserted in its place. The spring 8 acts to flatten or compress the tube 15 in the manner described, and also, due to 105 its pressure on the key 12, serves as a locking means for holding the key in rotated adjustment. This spring is, of course, of such width as to extend throughout the entire width of the portion of the tube being compressed, as shown in Fig. 6 of the drawings. 110 Also, the resiliency of the spring 8 serves to

prevent breakage of the tube in the event of the paste being lumpy or unusually thick, such as would occur if the tube were forced beneath a fixed compressing member.

5 By constructing the casing in the manner set forth, I provide a device which may be produced at very low cost and presents a neat appearance, this device also serving as a housing for the various elements for compressing the tube and for the upper portion of the tube. A casing constructed in this manner is especially adapted to use in bath rooms and similar places for supporting tubes containing tooth paste, soap paste, or 10 other materials used for toilet purposes. Of course, the device may be equally well used for compressing tubes containing paint or any other material in a pasty or semi-liquid form.

20 The form of the device shown in Figs. 7 to 9 inclusive, closely resembles that shown in Figs. 1 to 6, except that the spring 8 is replaced by a compressing roller 17 which is mounted in horizontal slots 18 and 19 in the 25 side walls 1 and 2, respectively, of the casing, for limited movement toward and away from the key 12. This roller is resiliently forced toward the key by the springs 20 which are mounted on a rod 21 secured in 30 the side walls of the casing and near the top thereof, these springs being wound about the rod and having their upper arms 22 in engagement with the under face of the top 35 11 of the casing. The roller 17 acts to 11 press the tube 15 in the same manner as spring 8 so as to expel the contents thereof, when the tube is wound upon key 12.

In the form of the device shown in Figs. 10 and 11, the hook slots 5^a and 6^a are made 40 somewhat longer than slots 5 and 6, so as to extend to within a short distance of the top 11 of the casing. A compressing roller 23 is rotatably mounted in the side plates 1 and 2 of the casing and is secured against movement in the casing. This roller 23 is mounted in the same plane as roller 17, which is forced toward the same by the springs 20 mounted on rod 21. These two rollers are so spaced as to provide a restricted passage 45 50 through which is inserted the flattened end portion 24 of the tube 25. When the key 12 is rotated so as to wind the tube onto the same, the rollers 17 and 23 act to compress the tube so as to expel the contents thereof.

55 In this form of the device, the tube 25 is of special form. In filling, this tube is provided with the elongated flattened end portion 24 which is held by any suitable means during the filling operation, thus leaving 60 the tube with the approximately cylindrical body portion and the elongated end portion 24 which is especially adapted to be inserted between the rollers 17 and 23 and into the slot of key 12. This tube having this

flattened end portion may be manufactured as a separate article and sold for use in connection with the device shown in Figs. 10 and 11 of the drawings, thus providing means whereby a special tooth paste or similar material may be manufactured and advertised in connection with these tubes.

What I claim is:

1. In tube holders, a supporting casing, a key rotatably mounted therein and adapted to have the flattened end portion of a collapsible tube secured thereto, and a resilient compressing member carried by the casing and normally forced toward the key, said member being so disposed as to exert pressure upon a tube being wound upon the key, so as to expel the contents thereof and form the body portion of the tube into a flattened strip extending longitudinally of the key so as to be easily wound onto said key.

2. In tube holders, a resilient tube engaging member adapted to engage a compressible tube moved into engagement therewith so as to expel the contents of said tube, and means for moving a tube into engagement with said member.

3. In tube holders, a casing, a key rotatably mounted therein and provided with means for receiving and holding the flattened end portion of a compressible tube, and means adapted to engage a tube as it is wound upon said key so as to compress the same and expel the contents thereof.

4. In tube holders, a casing, a key rotatably mounted therein and provided with a central longitudinally extending slot, and a resilient tube engaging member carried by the casing and normally pressed toward said key so as to engage a compressible tube wound upon the same and compress said tube so as to expel the contents thereof.

5. In tube holders, a casing, a key rotatably mounted therein and provided with a central longitudinally extending slot, said key being removable from the casing, and a resilient tube engaging member carried by the casing and normally pressed toward said key so as to engage a compressible tube wound upon the same and compress said tube so as to expel the contents thereof.

6. In tube holders, a casing having depending side walls provided with upwardly extending substantially hook-shaped slots, said slots being in alignment transversely of the casing, a key rotatably mounted in the hook portions of said slots and having a central slot adapted to receive the flattened end portion of a compressible tube, and a leaf spring secured in said casing and normally pressed toward said key so as to engage a tube wound upon the key so as to compress said tube and expel the contents thereof.

7. In tube holders, a casing, a key rota-

tably mounted in said casing and having a central slot adapted to receive the flattened end portion of a collapsible tube, and a leaf spring secured in said casing above the key and adapted to exert downward pressure thereon, said leaf spring acting to compress a tube secured to the key with the discharge nipple thereof directed downwardly so as to compress the tube and expel the contents thereof, said spring being of such width as to form the tube into a flattened strip which may be readily wound upon the key.

In testimony whereof I affix my signature in presence of two witnesses.

KENNETH A. CRISMON.
